UNITED STATES PATENT OFFICE.

CHARLES S. SHEPARD, OF BROOKLYN, NEW YORK, ASSIGNOR TO HIMSELF
AND LOUIS B. PRAHAR, OF SAME PLACE.

FASTENING FOR BAG, POCKET-BOOK, AND PURSE FRAMES.

SPECIFICATION forming part of Letters Patent No. 319,632, dated June 9, 1885.

Application filed April 4, 1885. (No model.)

To all whom it may concern:

Be it known that I, CHARLES S. SHEPARD, of Brooklyn, in the county of Kings and State of New York, have invented a new and useful 5 Improvement in Fastenings for Bag, Pocket-Book, and Purse Frames, of which the following is a full, clear, and exact description.

Reference is to be had to the accompanying drawings, forming a part of this specification, 10 in which similar letters of reference indicate corresponding parts in all the figures.

Figure 1 is a plan view of one of my improved fastenings shown as applied to a bag-frame. Fig. 2 is a side elevation of one part 15 of the frame and the part of the fastenings attached to it. Fig. 3 is a side elevation of a portion of the other part of the frame and the part of the fastening attached to it. Fig. 4 is a sectional end elevation of the frame and 20 fastening, taken through the line $x x$, Fig. 1. Fig. 5 is a plan view, partly in section, of the fastening and a portion of the frame.

The object of this invention is to provide 25 fastenings for bag, pocket-book, and purse frames which shall be simple in construction and convenient and reliable in use.

The invention relates to a fastening for bag, pocket-book, and purse frames constructed with a pair of studs attached to one part of 30 the frame, a pair of studs provided with knobs and attached to the other part of the frame, and a rod provided with a knob hinged to the one pair of studs and shutting down between the knobs of the other pair, as will be herein- 35 after fully described and then claimed.

A B represent the parts of a bag-frame.

To pairs of studs C, attached to the part A of the frame, are hinged sockets D, to receive the ends of the bag-handle.

40 To and between two studs, E, attached to the middle part of the part A of the frame, is hinged the end of a short rod, F, upon which is formed a knob, F', at such a distance from the hinged end of the said rod as to receive

between it and the studs E the knobs G', formed 45 upon the upper ends of two studs, G, attached to the middle part of the part B of the bag-frame at such a distance from each other that they must be sprung apart to allow the rod F to be forced down between their knobs G'. 50

Upon the free end of the rod F is formed a knob, F'', to serve as a handle in opening and closing the fastenings. With this construction the rod F is held from swinging out from between the studs G by the elasticity of the 55 said studs and by the knobs G', formed upon their ends. The rod F is held from being drawn out longitudinally from between the studs G by the knob F', which rests against the outer sides of the said studs G, so that the 60 fastening can be fastened and unfastened only by applying sufficient force to the outer end of the rod F to spring the studs G apart sufficiently to allow the said rod F to pass between the knobs G' of the said studs. 65

Having thus described my invention, I claim as new and desire to secure by Letters Patent—

1. A fastening for bag, pocket-book, and purse frames constructed substantially as herein shown and described, and consisting of two 70 pairs of studs, and a rod having a knob hinged to one pair of studs and shutting down between the other pair, as set forth.

2. In a fastening for bag, pocket-book, and purse frames, the combination, with the parts 75 A B of the frame, of the pair of studs E, attached to one part, the pair of studs G, provided with knobs G' and attached to the other part, and the rod F, provided with the knob F', hinged to the studs E and shutting down 80 between the knobs G' of the studs G, substantially as herein shown and described, whereby the said fastening can be readily fastened and unfastened, as set forth.

CHARLES S. SHEPARD.
